US00D500758S

(12) **United States Design Patent** (10) Patent No.: **US D500,758 S**
Widiaman et al. (45) Date of Patent: **** Jan. 11, 2005**

(54) **KEY BUTTON ARRANGEMENT FOR A HANDSET**

(75) Inventors: **Rudy Widiaman**, Woodland Hills, CA (US); **Duncan Burns**, Tarzana, CA (US)

(73) Assignee: **Nokia Corporation**, Espoo (FI)

(**) Term: **14 Years**

(21) Appl. No.: **29/204,087**

(22) Filed: **Apr. 26, 2004**

Primary Examiner—Jeffrey Asch

(74) *Attorney, Agent, or Firm*—Banner & Witcoff, Ltd.

(57) **CLAIM**

The ornamental design for a key button arrangement for a handset, as shown and described.

DESCRIPTION

FIG. 1 is a front view of a key button arrangement for a handset showing our new design; and,

FIG. 2 is a perspective front view thereof.

The broken line showing of the remainder of the handset is for illustrative purposes only and forms no part of the claimed design.
